UNITED STATES PATENT OFFICE.

DOUGLAS GWYN ROBINSON, OF WEYMOUTH, ENGLAND. ASSIGNOR OF ONE-HALF TO
WILLIAM SHERIDAN COLLINS, OF LONDON, ENGLAND.

ELECTRICAL FUSE.

Application filed April 7, 1925, Serial No. 21,260, and in Great Britain April 10, 1924.

This invention has reference to electrical fuse wire carriers for use with fuse bases of the cartridge or spring-clip type and is more particularly intended for use upon automobiles.

Hitherto it has been customary to supply fuse wires for certain electrical systems in glass cylinders with fixed metal caps, electrically connected to the ends of the enclosed 10 fuse wire, the said caps being engaged by suitable spring-clips upon a base or bracket. By reason of the variation in the sizes and distances apart of the spring-clips for different makes of lighting sets, it has been necessary for retailers to stock a comparatively 15 large number of different sized glass cylinders containing the "fuses" for replacements.

The present invention has for object to 20 provide an adjustable fuse wire carrier which can be used in almost all spring-clips of this type in current use, which carrier in addition contains sufficient reserve of fuse wire to enable the "fuse" to be quickly replaced when necessary. Thus a single model according to the present invention replaces 25 a number of carriers of different sizes as required for different electric lighting sets.

According to the present invention, I provide 30 an insulator body with split metal collars, hoops or the like slidable thereon and adapted to engage or press upon a piece of fuse wire arranged longitudinally of the insulator body. The collars or sliders may be 35 split transversely or circumferentially, so as to exert a constrictive action in order to grip the fuse wire on the exterior of the insulator body. These collars or sliders also act as the fuse terminals. Means are also 40 provided for holding the ends of the wire to maintain the latter in position while the collars are being slid into place.

Upon the accompanying sheet of drawings:

45 Figures 1 and 2 are respectively a front elevation, and a side elevation partly in section, of a fuse wire carrier, according to one form of the invention.

50 Figures 3 and 4 are side elevations of the same fuse carrier fitted to different brackets, the collars being adjusted to suit the different spacing of the spring clips upon the brackets.

Figure 5 is an end elevation of Figure 4.

Figure 6 is a side elevation of a modified 55 insulator body.

Figure 7 is a longitudinal section of another form of insulator body having an internal storage chamber for spare fuse wire.

Figures 8, 9 and 10 illustrate a further 60 modification in which the fuse wire is sunk in a longitudinal recess in the insulator.

Figure 11 shows a hollow body with the fuse wire passing longitudinally therethrough.

The insulator body *a* of the fuse carrier is preferably of elongate cylindrical shape and may be made of vulcanite, vulcanized fibre, porcelain or other suitable material. Detachable spring metal collars or "sliders" 70 *b* of split circular shape, movable along the body *a*, press upon and electrically engage the fuse wire *c* which is arranged longitudinally and externally of the insulator body *a*, the sliders *b* slipped upon the opposite ends 75 of the body *a* exercising a constrictive action so as to hold the said wire and insulator body firmly together. These sliders *b* not only make direct contact with the externally arranged wire *c*, but also clamp the wire *c* 80 against the body *a*, and serve as the fuse terminals. The ends of the wire *c* are also held fast by means hereafter described, whilst the collars *b* are adjusted in position.

The fuse wire *c* may be seated for part of 85 its length in a longitudinal groove or grooves *d* in the insulator body *a*, but remains always in electrical contact with the spring collars or sliders *b*, which are engaged electrically by the spring-clips *e* of the usual base or 90 bracket (see Figures 3 and 4).

The sliding members *b* enable the effective length of the fuse carrier to be adjusted and varied to fit the clips *e* upon the fuse-bases of different lengths, where the terminals or 95 clips vary in their distances apart; see Figures 3 and 4.

The insulator body *a* is preferably recessed intermediate of its length as at *a'*, to allow for the heating of the fuse wire *c* and 100 to provide for its expansion and contraction, the wire being cranked or bent into the recess, as shown.

The insulator body *a* may be provided at 105 its opposite ends with projecting terminal screws *f* as shown in Figures 1-5, the ends of the fuse wire *c* being wound round these screws for the purpose of mechanically se-

curing the wire *c* in position on the insulator body *a* independently of the spring collars or sliders. Thus during the removal or replacement of the collars *b*, the wire *c* is prevented from falling away from the insulator body, or from being dislodged from its correct position.

The coiled ends of the fuse wire *c*, wound upon the screws *f*, are of sufficient length to form a reserve of wire carried by or upon the insulator body *a*.

In the modification shown in Figure 6, the insulator body *a* is provided with integral headed necks *a*², the ends of the length of fuse wire being coiled or looped around said necks in such a way as to be outside and away from the collars *b*.

In another modification, see Figure 7, the insulator body *a* may be made hollow, the interior chamber *i* serving to contain one or more loops or lengths of fuse wire protected if desired by insulating blocks or pads *j* located in the bore of the chamber *i*, the hollow ends of the bore being closed by screws *f* or the like. The chamber *i* need not extend completely through the body *a*, and in such case a headed neck such as *a*² may be formed at one end of the body and a terminal screw *f* fitted at the other end of the body to close the open end of the chamber, the neck and screw respectively serving for the anchorage of the ends of the fuse wire actually in use.

In the modification illustrated in Figures 8 to 10, the insulator body *a* is cylindrical in shape with a longitudinal groove *g* adapted to receive the inwardly cranked ends *b*¹ of split metal collars *b* which thus conform to the shape of the periphery of the body *a*; each of these split collars is slidable upon the cylindrical body, the fuse wire being gripped between the inwardly turned ends *b*¹ of the two collars so as to be enclosed in the groove *g* extending longitudinally of the insulator.

Where the insulator body is made hollow, the fuse wire may, as shown in Figure 11, extend longitudinally through the bore *i* in the insulator *a*, its projecting ends being turned over on the exterior where they are engaged by locking screws *h* arranged intermediate of the two sliding collars *b*. Thus the sliding collars make contact with those portions of the wire *c* leading from the open ends of the body *a* to the set-screws *h* on the exterior of the same. In this case the sliders *b* are shown formed as helical spring coils to provide the constrictive spring grip without any break in continuity circumferentially.

The split spring sliders by their constrictive action automatically retain their position after adjustment and provide sufficient pressure upon the fuse wire to ensure sound electrical contact therewith while themselves making contact with the spring-clips or arms of the fuse base.

By means of this invention a blown "fuse"

can be quickly replaced; after unwinding the reserve wire stored in or upon the carrier, the wire can be drawn out to the required extent and engaged with the two sliders, for the purpose of repairing the "fuse". The fuse carrier is quickly adjustable to suit the length of the base on a given switch board, and any ordinary gauge fuse wire can be employed. Moreover, the fuse carrier can be speedily fitted when required with a fresh supply of spare fuse wire.

Having thus described my invention, what I claim is:—

1. In an electrical fuse, the combination of spring contact clips, an insulator body, a fuse wire arranged upon the exterior of said body and metal clamping members slidably arranged upon said body, said clamping members pressing said fuse wire against said insulator body and being detachably engageable in said spring contact clips, said clamping members being adjustable longitudinally of said insulator body to correspond with the distance between said spring contact clips.

2. An electrical fuse, comprising an insulator body, a fuse wire arranged externally of said body, a pair of variably interspaced metal sliders mounted upon said body and constrictively acting upon said fuse wire, said sliders forming the fuse terminals; and means for anchoring the extremities of said fuse wire to said insulator body.

3. An electrical fuse, comprising an elongated insulator body, said body being grooved exteriorly; a length of fuse wire carried upon said body and arranged in the grooved portion of said body; and a pair of metal sliders fitting upon said body and having means for making contact with said fuse wire in said groove, said sliders being adjustable as to distance apart and acting as the fuse terminals.

4. An electrical fuse, comprising an insulator body; a fuse wire arranged externally of said body; variably interspaced metal clamping members slidably arranged upon said body, said slidable members pressing directly upon the fuse wire and acting as the fuse terminals; and means for holding the fuse wire in place upon said body whilst the slidable members are being moved therealong.

5. An electrical fuse comprising an insulator body; a fuse wire arranged externally of said body; variably interspaced metal clamping members slidably arranged upon said body, said slidable members making electrical contact with said fuse wire and serving also as the fuse terminals; and means for carrying a reserve supply of fuse wire upon said insulator body.

6. An electrical fuse of the cartridge type, comprising an insulator body, metal sliders fitting upon said body, said sliders adjust-

able longitudinally of said body, a fuse wire arranged along said body and a pair of screws engaged in opposite ends of said body, the extremities of said fuse wire being wound upon said screws.

7. In combination with an electrical fuse holder having interspaced spring clips, a cartridge fuse comprising an insulator, metal sliders fitting upon said insulator, said sliders being adjustable as to distance

apart longitudinally of said insulator to suit the spacing of said spring clips, a fuse wire arranged along said insulator and passing beneath said sliders, means for anchoring said fuse wire to said insulator ¹⁵ independently of said sliders, and means for carrying a reserve supply of fuse wire upon said insulator.

In testimony whereof I affix my signature.
DOUGLAS GWYN ROBINSON.
